M. E. TYNES

COMBINED GAME AND TOY

Filed Feb. 1, 1924

Fig. 1.

UNITED STATES PATENT OFFICE.

MINOR EUGENE TYNES, OF NEW ORLEANS, LOUISIANA.

COMBINED GAME AND TOY.

Application filed February 1, 1924. Serial No. 689,953.

To all whom it may concern:

Be it known that I, MINOR E. TYNES, a citizen of the United States, residing at New Orleans, in the parish of Orleans and 5 State of Louisiana, have invented a new and useful Combined Game and Toy, of which the following is a specification.

This invention relates to games and toys and more particularly to chance controlled 10 games.

The object of the invention is to provide a gravity operated toy to actuate means for projecting playing pieces into pockets.

Another object is to provide a device of 15 this character in which a rotary sweep is mounted to travel from one end to the other of a support and in the path of which is located means for propelling playing pieces so that the device performs the function of 20 both a toy and a game.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, may be made within the scope of what is claimed without 30 departing from the spirit of the invention.

In the accompanying drawings:

Figure 1 represents a side elevation partly in section and with parts broken out of a device embodying this invention.

Fig. 2 is a horizontal section taken on the line 2—2 of Fig. 1.

In the embodiment illustrated a base board 1 is shown which may be of any desired configuration being here shown circular and 40 having an upstanding flange 2 at its perimeter. This board is made concave on its upper face and has a centrally disposed boss 4 through which a bore extends terminating in a recess 5 formed in the lower face of the 45 board. A standard 6 extends through said boss and is secured by lock nuts 7 and 8 located above and below the board respectively, the recess 5 forming a housing for nut 8.

The standard 6 which may be of any desired height is equipped at its upper end with an eye 9 which forms a hand-grip for moving the device from place to place and for steadyng it when required.

A coiled wire 10 is wound around the 55 standard 6 being connected at one end to the loop or eye 9 and at its other end to the

standard. This coil 10 is constructed of heavy wire, the pitch of the spiral being varied to increase or diminish the speed of rotation of a sweep designed to travel 60 thereon.

This sweep comprises a rod 15 bowed midway the ends thereof and provided with a laterally extending loop 16, the members of which preferably lie in contact with each other and the loop is designed to be entered in the spirals of the coil 10 and to travel thereon, said spirals operating as a track for the sweep. The ends of the rod 15 are pivotally engaged with Figures 17 and 18 70 which may be of any desired shape, a man on horse-back being here shown. These figures are pivotally mounted above their centers of gravity so that they will automatically assume upright positions. As 75 shown, one figure is mounted on one side of the sweep and the other on the opposite side so that they will be properly balanced. It is of course understood that the parts will all be so positioned that the sweep when 80 the loop 16 is inserted in one of the spirals of the coil, will balance perfectly upon the coiled wire and will extend approximately at right angles thereto.

Loosely mounted on the lower end of the 85 standard 6 is a winged member composed of a piece of wire bent to form downwardly inclined diverging wings 11 with coils 13 and 14 formed at the top and bottom of the wings and which loosely engage the standard. An L-shaped arm 12 is carried by the upper coil 13 the short arm 12^a of which projects laterally at right angles to the standard while the long arm 12^b extends upward and is located in the path of the rotary 90 sweep so that when said sweep reaches a predetermined point in its descent it will engage the arm 12^b and rotate the winged member which operates playing pieces 19 to throw them outward over the board with 95 a view to causing them to enter pockets 20 formed in board 1. These playing pieces 19 are shown in the form of marbles which when placed on the board will gravitate to the center thereof and when struck by the 100 wings 11 will be thrown out over the board and some of them at least will enter the pockets 20.

Six pockets 20 are here shown numbered 110 consecutively from 1 to 6.

In the use of this device the marbles 19 are placed on the board and owing to its

concave face will gravitate to the center and be located in the path of the wings 11. The sweep is then positioned as shown in Fig. 1 at the upper end of the standard 5 with the loop 16 engaged with the track 10. When released this sweep will move downward by gravity along the spiral track 10 gaining speed as it moves so that when it reaches the point where the arm 12^b is located in the path thereof it will carry said arm with it and swiftly revolve the winged member connected with said arm causing said wings to engage the marbles 19 and throw them out over the board into the 15 pockets 20. The object of the game is to get as many of the marbles into the pockets as possible the score counting according to the numbers on the pockets in which the marbles are thrown, for instance if three 20 marbles enter pockets 2, 3 and 4 the score will be nine.

When the sweep reaches the limit of its downward movement the loop 16 is lifted out of engagement with the coiled wire and 25 replaced at the top of the stand ready for the next trip. Any number of trips may be made according to the rules governing the game.

I claim:

30 1. A base board having pockets, a standard rising therefrom, a member rotatable on said standard and having wings extending over said board adjacent thereto, a rotatable gravity member adapted to travel 35 on said standard, and means carried by said first mentioned rotatable member and extending into the path of said gravity mem-

ber and adapted to be engaged and rotated thereby.

2. A base board having pockets, a standard rising therefrom, a member rotatable on said standard and having wings extending over said board adjacent thereto, a rotatable gravity member adapted to travel 40 on said standard, means carried by said first mentioned rotatable member and extending into the path of said gravity member and adapted to be engaged and rotated thereby, and playing pieces to be located 45 on said board in the path of said wings whereby they are moved over the board 50 with a view to entering said pockets.

3. A base board having a concave upper face with pockets located adjacent its perimeter, a standard rising centrally from said board, a member mounted loosely on said standard and having laterally extending wings located in proximity to the board, an arm extending upwardly from said member and spaced laterally from said standard 55 and a rotatable gravity member adapted to travel on said standard and engage said arm whereby the winged member is rotated with the gravity member, and playing pieces to be located on the board in the path of the 60 winged member.

In testimony that I claim the foregoing as my own, I have hereto affixed my signature in the presence of two witnesses.

MINOR EUGENE TYNES.
